UNITED STATES PATENT OFFICE.

JOHN J. McINTIRE, OF SAN FRANCISCO, CALIFORNIA.

DESIGN FOR A TOY.

53,926.

Specification for Design.

Patented Oct. 7, 1919.

Application filed August 15, 1918. Serial No. 250,085. Term of patent 7 years.

To all whom it may concern:

Be it known that I, JOHN J. McINTIRE, a citizen of the United States, residing in the city and county of San Francisco and State of California, have invented a new, original, and ornamental Design for Toys, of which the following is a specification, reference being had to the accompanying drawings, forming part thereof.

The figure is a view in perspective of the toy, showing my new design.

I claim:

The ornamental design for a toy, as shown.
JOHN J. McINTIRE.
